(57) **CLAIM**

The ornamental design for a star lighting fixture panel assembly, as shown and described.

DESCRIPTION

FIG. 1 is a bottom perspective view of a star lighting fixture panel assembly and a surrounding environment thereof; FIG. 2 is a front elevational view of the star lighting fixture panel assembly;

FIG. 3 is a rear elevational view thereof;

FIG. 4 is a right-side elevational view thereof;

FIG. 5 is a left-side elevational view thereof;

FIG. 6 is a top plan view thereof;

FIG. 7 is a bottom plan view thereof; and,

FIG. 8 is an exploded bottom perspective view thereof.

The broken lines in the drawings illustrate portions of the star lighting fixture panel assembly which form no part of the claimed design.
